TRACK RAIL FASTENING

John W. Mathias, Upper Darby, Pa., assignor of
one-half to John L. Martin, Philadelphia, Pa.

Application September 1, 1938, Serial No. 227,898

7 Claims. (Cl. 238—338)

The fastening of this invention is particularly adapted to high speed railroad interurban open track-subway and elevated track construction where, due to its open character, control is needed over expansion and contraction in order that modern joints such as Thermit, flash weld or any continuous welded joint may be utilized.

Track construction has retained to a great extent the same original method of fastening rails to wood ties, by holding merely the edges of the base of the rail by means of hook head spikes, screw spikes, or screw spikes and clips, either with or without base plate fastenings using both sides of the rail base edges for a fastening base, resulting in proportionately small bearing on the rail base itself in fastening rails to ties. Tie plates and different combinations of tie plates and spikes and clips are used; however, they all fall short of recognizing and using the full area of the rail base and part of the web of the rail as a load distributing agent.

The objects of the present invention are to provide an adequate open track fastening adapted to meet the requirements of the advances made in new equipment, higher speeds and heavier loads and which permits of the continuous welding of rail joints without creepage in an open track construction; to use the full area of the rail base and a large part of the area of the web of a rail as a load distributing agent, thus increasing the bearing and stress distributing area; to utilize the rail itself for hold down anchorage; to interlock the parts of the fastening in such a way that they act as a unit to eliminate creeping of the rails and check sidewise stresses by the bracing action of the fastening; to hold the rails to gauge and to avoid the use of bolts or the like between the fastening and rail.

Other objects of the invention will appear from the following description at the end of which the invention will be claimed.

Generally stated the invention consists in a tie plate adapted for application to a tie and having flanged outer edges and shouldered side edges adapted to abut on the opposite edges of the rail base, a pair of clip anchors adapted respectively to abut at one end on the tie plate outer flanges and each having at the other end an upstanding T head adapted to bear on the adjacent edge of the rail flange and each having a knee loop extension adapted to pass under and bear on the rail base and to lie alongside the tie and extend to the opposite edge of the rail base, a pair of rail clips curved in consonance with the rail base and web and each adapted to abut on

one of the flanges at the outer edges of the tie plate and on the adjacent rail base and web and each provided with a T slot adapted to receive one of the T heads and to be held down thereby.

The invention also consists in the improvements to be presently described and finally claimed.

In the following description reference will be made to the accompanying drawing forming part hereof and in which,

Figure 1 is a perspective view partly in cross section illustrating a track rail fastening embodying features of the invention.

Fig. 2 is a similar view showing the parts of the rail fastening in detached position.

Fig. 3 is a perspective view illustrating a modification in which the clip anchor is provided at its side edges with a flange, and

Fig. 4 is a similar view of another modification in which the clip anchor is provided with a lip for engaging the rail base.

In the drawing *a* indicates a portion of railway rail and *b* indicates a portion of the tie. *1* indicates a tie plate having at its sides flanges *2*. *3* indicates shoulders at the side edges of the tie plate and they are adapted to abut on the opposite edges of the rail base. They are shown as confined to the edges of the tie plate so as to accommodate other parts which will be herein-after described. There are a pair of clip anchors *4* and since they are duplicates it is only necessary to describe one of them. These clip anchors abut on the flanges *2* and they are each provided with a T head adapted to bear on the adjacent edge of the rail flange. The clip anchor *4* is also provided with an extension from one of its lateral edges and this extension includes a loop *6* and knees *7* so that it is a knee loop. The knee loop passes under and bears on the bottom of the rail base and it extends along the tie to the opposite edge of the rail base and at its end it may be provided with a hook *8*. There are a pair of rail clips *9* and a description of one of them will suffice because they are duplicates. The rail clip *9* is curved in consonance with the rail base and web and it abuts on the flange *2* and it is provided with a T slot *10* adapted to receive the T head *5* and to be held down thereby. The tie clips extend over the rail base and up the web of the rail to the neutral axis. *11* indicates a

friction and compression agent such as Masonite (compressed wood) or rubber, and it is interposed between the rail, shoulder, and tie plate, and between the rail clip and rail web and base. *12* indicates screw spikes for attaching the de-

30

scribed fastening, which is locked to the rail, in place on the tie.

From the foregoing description it is evident that the entire rail base above the tie plate and the web of the rail up to the neutral axis of the same is used as a bearing agent in fastening the rail to the tie. This increases the bearing area and stress distribution area from the usual four square inches to fifty-six square inches or thereabouts and the above area is coupled to the opposite side of the rail base through a common anchorage, using the rail itself for hold down anchorage. In assembling the parts the tie plate 1 is first placed on the tie 2, and the rail 3 is then placed on the tie plate with the edges of its base in contact with the flanges 3. The clip anchors 4 are then applied with their T heads 5 in contact with the edge of the rail base and to one side of the flange 3 and the outer edges of the clip anchor are in contact with the tie plate flanges 2. The knee loop extensions pass along the tie and under the rail and the knees 7 abut on the bottom of the rail base, the hook 8 engages the head of the rail base opposite the edge where the slip anchor is arranged. The hook 8 may be hammered or otherwise forced into contact with the rail base. The rail clips 9 are then applied with the T heads 5 through the T slots 10 and they are driven inward until their outer edges lie in engagement with the flanges 2 of the tie plate. The rail and rail fastening are thus completely interlocked so that they act as a unit rather than as independent parts. The function of the screw or other spikes 12 is merely to connect the rail fastening and the tie and during the assemblage of the parts of the fastening the openings 13 for the screw or other spike 12 are brought into alignment. The holding power and frictional resistance of the fastening opposes creeping of the rail in either direction. Furthermore the bracing action of the described fastening checks sidewise stresses. The Masonite or other material which is compressed between the shoulders of the tie plate and between the base of the rail and top of the tie plate prevents cutting or wearing of the tie plate by direct contact of metal or metals and furthermore that material has a sound deadening effect and eliminates noise to a great extent. It may be remarked that there are no bolts or the like for securing the rail fastening to the rail and in the usual type of rail fastenings the stresses from the rail to the fastener is distributed entirely through a bolt or the like which is constantly being worked or stressed. The described parts of the fastening can be manufactured at little expense and are easily and quickly assembled.

Since the extensions 6 lie on opposite faces of a tie 2, they serve to square the tie and the rail and rail fastening. When the extensions 6, are in the form of loops they are springy which is an advantage in some cases. The purpose of bevelling or undercutting the ends of the clip anchors 4 and rail clips 9 is to facilitate their assembly in the flanges 2 by driving them after they have been properly mounted in respect to the rail. The outer walls of the head of the T-slot 10, are also bevelled or undercut to facilitate the entrance of the T-head 5 when the rail clips are driven to place.

The embodiment of the invention described is particularly adapted to high speed railroad interurban open track speedway and elevated track construction but for other uses it is not always necessary or desirable to use the complete con-

struction described. For example, the tie-plate may be omitted and use made of the clip anchors and rail clips. In that case the clip anchors should be provided with upturned flanges indicated at 2^a in Figure 3, and the tie-plate and rail clips may be omitted and in that case the clip anchors are modified as indicated in Figure 4 so as to retain the extensions 6 and to provide lips 9^a for engagement with the upper surface of the rail base.

It will be obvious to those skilled in the art to which the invention relates that modifications may be made in details of construction and arrangement and in matters of mere form without departing from the spirit of the invention which is not limited to such matters, or otherwise than the prior art and the appended claims may require.

I claim:

1. Means for fastening railway rails to ties comprising the combination of a tie plate adapted for application to the tie and having upstanding flanges at its outer edges and shouldered intermediate portions said portions adapted to abut on the opposite edges of the rail base, a pair of clip anchors superposed on the tie plate and adapted respectively to abut at one end on said tie plate flanges and each having at the other end an up-standing T head wholly located above the tie plate and adapted to bear on the adjacent edge of the rail flange and each having a knee loop adapted to pass under and bear on the bottom of the rail base and to pass alongside the tie to the opposite edge of the rail base and there engage the bottom edge and top of the rail base, and a pair of rail clips curved in consonance with the rail base and web and each adapted to abut on one of said tie plate flanges and on the adjacent rail base and web and each provided with a T slot adapted to receive one of the T heads and to be held down thereby said plate, anchor and clips being secured together by their interlocking relation with the rail and with each other and being secured to the tie by additional means.

2. Means for fastening railway rails to ties comprising the combination of a tie plate adapted for application to the top of a tie and having side flanges and intermediate shoulders, a pair of clip anchors superposed on the tie plate and each adapted to bear on one of said flanges and having an up-standing T head wholly located above the tie plate and aligned with one of said shoulders and having a knee loop adapted to extend at the side of the tie plate into alignment with the T head of the other clip anchor and there engage the bottom side and top of the rail base as well as engage the opposite under face of the rail base, rail clips having T slots adapted to receive said T heads and to abut on the flanges of the tie plate and on the base and web of the rail and means securing said plate, anchors and clips to the tie.

3. Means for fastening railway rails to ties comprising the combination of a tie plate underlying the rail and overlying the top surface of the tie and having upstanding side flanges and intermediate shoulders said shoulders being adapted to engage the edges of the base of the rail, clip anchors superposed on the tie plate and having up-standing T heads and provided with extensions adapted to engage the under face of the base of the rail and also one edge of the far side thereof, rail clips having slots for the T heads and adapted to engage the top of the base and a

substantial portion of the web of the rail, and means for securing the clip anchor and rail clip to the tie plate and tie.

4. The combination substantially as described in claim 3 in which said securing means comprises spikes which penetrate the rail clips, clip anchors, and tie plate and enter the ties to hold down the fastening elements and rail to the tie.

5. Means for fastening railway rails to ties consisting of a tie-plate adapted for insertion between the upper surface of the tie and the bottom surface of the rail and shouldered intermediate its side edges to engage both edges of the rail base and having upstanding flanges at said side edges, a pair of clip anchors having T-heads overlying the tie plate and other means underlying the rail base at each edge thereof, a pair of rail clips engaging said upstanding flanges and also the upper face of the rail base and parts 15 of the web and having T-slots engaging the T-heads, whereby said anchors and clips are adapted to be clamped together and to the top and bottom parts of the rail base and to the rail web, and means for securing the clip anchor and rail 20 clip to the tie plate and tie.

6. Means for fastening railway rails to ties consisting of a pair of clip anchors adapted to be

disposed at the respective sides of a rail and each having an extension arranged along the side of the tie and adapted to under span the rail and to engage the under face of the rail base at both sides thereof and to engage the far edge 5 of the rail base, a pair of rail clips adapted to be superposed on the clip anchors and shaped to engage the top face of the rail base and a portion of the web, means interposed between the rail clips and clip anchors for clamping them together 10 in pairs, a tie plate upwardly flanged to engage the rail base and the ends of the clips and adapted to be superposed between the top surface of the tie and the rails, anchors and clips, and means securing said anchors and clips to the tie. 15

7. In means for fastening rail way rails to ties, a tie plate, clip anchors and rail clips arranged on top of said plate on the same single tie, T-heads on said anchors and T-slots in said clips located wholly above the tie plate and interconnecting 20 the anchors and clips in pairs, means for fastening the clips and anchors to the top of said tie, said clip anchors each having an extension adapted to contact the opposite side of the same tie and to under pass a rail and engage the far edge 25 thereof.
